UNITED STATES PATENT OFFICE.

MORGAN HOGAN, OF UTICA, NEW YORK, ASSIGNOR TO BEECHER M. CROUSE, OF UTICA, NEW YORK.

UNION SUIT.

1,116,891.

Specification of Letters Patent. Patented Nov. 10, 1914.

Application filed April 23, 1912. Serial No. 692,646.

To all whom it may concern:

Be it known that I, MORGAN HOGAN, a citizen of the United States, residing in Utica, New York, have invented certain improvements in Union Suits, of which the following is a specification.

My invention relates to that class of union suits in which the crotch opening is normally closed by means of a pair of overlapping flaps, one object of my invention being to so construct such a union suit that the crotch-closing flaps will be retained in the closed condition without the use of buttons or equivalent fastenings; another object being to provide for staying or reinforcing that portion of the front of the body web above the crotch and also at the lower end of the buttonhole strip in an open front garment, and a still further object being to so construct the crotch-closing flaps that they are well calculated to withstand the strains to which they are subjected in the use of the garment. These objects I attain in the manner hereinafter set forth, reference being had to the accompanying drawing, in which—

Figure 1 is a front view of sufficient of a union suit to illustrate my invention; Fig. 2 is a rear view of the same; Fig. 3 is a rear view of the blank for the union suit before the crotch-closing flaps are applied thereto; Fig. 4 is a view of the blank of which each of said crotch-closing flaps is composed, and Fig. 5 is a view showing the position assumed by the members of said flap when it is applied to the union suit.

In the drawing, 1 represents the body and 2, 2^a, the upper portions of the legs of the union suit, the latter, in the garment which I have selected for illustrating my invention, being one of that type in which the body is open in front, one of the edges of this open front of the body portion being provided with a row of buttons and the other with a buttonhole strip 3.

The body and legs may consist of a seamless tubular web or flat and folded web or webs, as may be desired, but in either case the web will be severed on central longitudinal lines so as to form front edges 4 and rear edges 5 at the inner side of one leg, and corresponding edges 4^a and 5^a at the inner side of the other leg, the incision corresponding with the rear portion of the garment being longer or deeper than that cor-

responding with the front portion, so that it will extend up into the back of the garment body some distance above the crotch and thus provide rear edges 5 and 5^a, as shown in Fig. 3, whereby when the leg portions of the garment are spread, as shown in Fig. 3, triangular incisions will be formed, that at the rear being deeper than that at the front. In connection with the blank thus prepared I use two crotch-closing flaps, each consisting of a blank 7 of the character shown in Fig. 4, said blank having, by preference, a straight upper edge 8 and straight and parallel side edges 9 and 10, and having at its lower end a laterally projecting gusset 11, which is secured to the lower end of the blank 7 by an angular seam 12, and presents an inclined outer edge 13 and other edges 14 and 15, the latter, by preference, being at a right angle to one another, as shown in Fig. 4. In applying these flaps to the blank shown in Fig. 3, the upper end of the flap which is used in connection with the right leg 2 is secured to the back of the body web, as at 16, (Fig. 2) in line or thereabouts with the top of the rear incision but on the left side of the central longitudinal line of the body, and the edge 10 of said flap is secured to the edge 6 of said rear incision, as shown at 17 in Fig. 2. The gusset 11 being turned up, as shown at Fig. 5, its edge 13 is secured to the edge 4 of the front incision above the point 18, as shown at 19, Fig. 1, and the upper edge 15 of the gusset is secured to the front web of the body at a point at or above the top of the front incision but on the left side of the central longitudinal line of the body, and the edge 10 of said flap is secured to the edge 6^a of said rear incision as at 17^a, (Fig. 2), the edge 13 of the upturned gusset being left free. In like manner the top edge 8 of the flap which is used in connection with the left leg 2^a of the garment is secured to the back of the body web at or about the top of the rear incision and on the right hand side of the longitudinal central line of the body as at 16^a, and the edge 10 of said flap is secured to the edge 6^a of said rear incision as at 17^a, Fig. 2, the edge 13 of the upturned flap being secured to the edge 4^a of the front incision above the point 18^a as at 19^a (Fig. 1) and the upper edge 15 of the gusset being secured to the front web of the body at or above the top of the front incision, as at 20^a (Fig. 1). The last applied flap overlaps that first applied, as shown in Figs. 1 and 2, so as to effectually close the opening in the

body, the flaps retaining the closed position without the use of buttons or other fastenings. When it is desired to uncover the opening in the body web, the free edges of 5 the flaps can be readily drawn apart laterally.

In order to complete the union suit the edges 4 and 5 and 4^a and 5^a of the front and rear incisions are sewed together as at 10 21 and 21^a down to the bottom of the leg, and the lower portions of the leg webs may be tapered in the usual way if it is desired to shape said legs at the ankle.

The seams 20 and 20^a whereby the upper 15 edges of the upturned gussets 11 are secured to the front web of the garment body constitute a stay for said front web above the crotch opening, and below the opening in the front of the garment body, and thus 20 enable this portion of the body web to better resist the strains, which, in the use of the garment, are exerted upon it at this point.

The member 11 of each flap is made in the 25 form of an attached gusset both for the purpose of saving waste in cutting and in order that the wales of stitches may run lengthwise in the gusset as well as in the main web of the flap, the member 11 of the 30 flap being thereby stronger and better able to resist the strains upon it than it would be if the said member 11 was integral with the body member 7 of the flap, for in the latter case the wales of stitches in the member 11 would run in a direction transversely 35 to its length.

The sewing together of the various parts can also be effected more readily when the wales of two parts to be united run in the 40 same direction than when the wales of one part run in one direction and those of the other part in another direction.

I claim:

1. A union suit having, at front and rear, 45 central incisions, said rear incision extending some distance up the back of the garment, in combination with a pair of overlapping flaps constituting a closure for the opening in the garment body, each flap 50 consisting of a strip having a tapering lower end and upturned gusset with tapering lower

end united to the tapering lower end of the strip, said gusset also having an inclined side, the top of the flap being secured to the back of the body web at about the top 55 of the rear incision, one edge of each flap being secured to the corresponding edge of said rear incision and the other edge of the flap being free and the inclined edge of the upturned gusset being secured to an 60 edge of the upper portion of the front incision, its other edge being free and constituting a continuation of the free edge of the back portion of the flap and the top edge of said upturned gusset being secured 65 to the front web of the body above the crotch.

2. A union suit having, at the front and rear, central incisions, said rear incision extending some distance up the back of the 70 garment, in combination with a pair of overlapping flaps constituting a closure for the opening in the garment body, each flap consisting of a strip having a tapering lower end and upturned gusset with tapering 75 lower end united to the tapering lower end of the strip, said gusset also having an inclined side and consisting of a separate web having stitch wales running longitudinally of the gusset and at an angle 80 to the wales of the main portion of the flap, the top of each flap being secured to the back of the body web at about the top of the rear incision, one edge of each flap being secured to the corresponding edge of 85 said rear incision, and the other edge of the flap being free, one edge of the upturned gusset of each flap being secured to the upper portion of the front incision, its other edge being free and constituting a continuation 90 of the free edge of the back portion of the flap, and the top edge of said upturned gusset being secured to the front web of the body above the crotch.

In testimony whereof, I have signed my 85 name to this specification, in the presence of two subscribing witnesses.

MORGAN HOGAN.
